UNITED STATES PATENT OFFICE.

HERMAN P. CLAUBERG, OF HASBROUCK HEIGHTS, NEW JERSEY, ASSIGNOR TO R. HOE & CO., INC., OF NEW YORK, N. Y., A CORPORATION OF NEW YORK.

FOLDING DELIVERY.

Application filed July 25, 1925. Serial No. 45,969.

This invention relates to certain improvements in folding deliveries which have been designed for use particularly in connection with printing machines, though useful in other relations.

In certain types of deliveries, particularly those employing a rotary folding mechanism, the product is folded off by being tucked into a pair of nipping jaws carried 10 by the folding cylinder, a blade being employed for tucking the product into the jaws. As the cylinder rotates the product is taken around the cylinder and folded, and after 15 folding is taken from the folding cylinder by a delivery cylinder from which it is finally delivered in any desired way. The delivery cylinders are provided with sheet taking devices, and where these sheet taking devices, as is the case in many instances, 20 are grippers trouble has been experienced in transferring the folded product to the grippers of the delivery cylinder, due to the fact that the folded edge of the product is frequently not entirely free from the nipping 25 jaws and lies within the periphery of the folding cylinder so that the grippers of the delivery cylinder miss it, thereby causing a choke. In order that the grippers on the delivery cylinder will have time to properly 30 act, it is desirable that the folded edge of the product should be substantially in a line with the surface of the folding cylinder at the time the grippers act.

It is a special object of the present invention to provide a construction where a folded product is transferred from a rotary carrier having nipping jaws to a delivery cylinder or carrier having grippers which will act to free the folded edge of the product 35 from the jaws and cause it to lie in substantially a line with the surface of the carrier so that the gripper will take it at the proper time without a miss.

A further object of the invention is to 40 provide such a construction which shall be simple, of few parts, and which will not interfere with the operation of the nipping jaws or of the grippers.

With these and other objects not specifically referred to in view, the invention consists in certain novel parts, arrangements and combinations which will be described in connection with the accompanying drawings and the novel features pointed out in the 45 claims hereunto annexed.

In the drawings,—

Figure 1 is an end elevation, more or less diagrammatical and partly broken away, of the delivery end of a printing machine, the front frame being removed;

Figure 2 is a detail side view of the folding cylinder shown in Fig. 1;

Figure 3 is an enlarged sectional view, partly broken away, showing the nipping jaws and showing the parts in the position 65 they occupy when the product is held by the jaws;

Figure 4 is a view similar to Fig. 3 showing the position of the parts when the jaws have released the product and the product 70 is in position to be seized by the grippers;

Figure 5 is a view similar to Figs. 3 and 4 showing the position of the parts when the product has been taken by the grippers. and

Figure 6 is a detail view showing the form of spring preferably employed for freeing the product from the nipping jaws.

Referring now to these drawings, the machine selected to illustrate the invention is 80 the delivery end of a printing machine in which the delivery includes a rotary folder by which the products are folded as they come from the machine. It will be understood, however, that the invention is capable 85 of use in other types of mechanism where a folded product is transferred by means of nipping jaws to a delivery mechanism having sheet taking devices in the form of grippers.

In the drawings the various mechanisms are supported in side frames 1; 2, of any usual or desired construction. In the particular machine illustrated the web W is forwarded between a pair of cylinders 3, 95 4 which may be cutting cylinders, a guide, as 5, being provided for guiding the cut sheets to the folding cylinder. From the cutting cylinder the products are taken by a cylinder 6 mounted on a shaft 7 by means of 100 sheet taking devices, as pins 8. This cylinder 6 is provided with folding blades 9, three such blades and three such sheet taking devices being shown in the particular construction illustrated. The blades 9 tuck 105 or fold off the product into the jaws of a folding cylinder 10 supported on a shaft 11, a desired number of these nipping jaws being provided. The construction of these is all the same and a description of one will 110

suffice for all. As shown, this construction usually comprises a pair of jaws having gripping surfaces 12, 13, these jaws being mounted on shafts 15, 16, and intergeared 6 as indicated at 17, these shafts being mounted in a recess 18 cut in the cylinder wall.

These shafts are operated in any suitable manner to grip and release a sheet. As shown, one of the shafts, as the shaft 16, 10 projects beyond the cylinder wall and carries cam roll 19 cooperating with the cam 20 on a hub 21 on the shaft 11, before referred to. From the folding cylinder 10 the products are transferred to a delivery, 15 which in the present instance includes a delivery cylinder 22 provided with sheet taking grippers 23, these grippers being carried on arms 24 on rock shaft 25 suitably supported in a recess 26 in the cylinder wall, 20 these grippers being operated to open and close in any usual manner.

In accordance with the invention, means are provided for freeing the product from the nipping jaws and causing it to assume 25 a position substantially in line with the surface of the cylinder. These means may vary, but they will, however, include resilient devices against which the product is drawn by the nipping jaws so that when the nipping 30 jaws are operated to release the product these resilient devices will act to force the product outwardly and cause it to assume a position in line with the surface of the cylinder, as shown in Fig. 4, so that it will 35 be surely seized by the grippers. In the specific construction disclosed these devices are in the form of flat springs, indicated generally by the numeral 27 in Fig. 6, any desired number of these springs being distributed 40 along the cylinder, four such springs being shown in Fig. 2. These springs are, as shown, generally bowed shape and are provided with upstanding legs 28 by which they may be secured in the recess 18 of the cylinder, as by means of 45 screws 29. These springs are preferably free at their other ends and the free ends are flattened, as indicated at 30. Furthermore, the springs will, in the best constructions, be 50 provided with a hump 31 forming in effect a shoulder 32 at the rear of the hump.

The product is drawn in by the nipping jaws against these springs causing the 55 springs to assume the position shown in Fig. 3, the hump forming a sort of stop or guide for the folded edge of the product. When the nipping jaws are operated to release the product the springs force the product upwardly to the position shown in Fig. 4, the 60 hump assisting in this movement. In order to prevent the folded edge of the product from being forced outwardly too far, stops 33 are provided against which the flattened ends 30 of the springs bear, as shown in 65 Figs. 4 and 5, so that the product is caused

to lie in a line substantially with that of the surface of the cylinder.

From the delivery cylinder 22 the product may be finally delivered in any way, as by a tape delivery, indicated by the numeral 35, 70 though it will be understood, of course that any desired delivery may be employed.

With the construction shown and described the product is positively cleared from the bite of the nipping jaws and is 75 correctly positioned on the surface of the roll to enable it to be surely taken by the grippers, so that no missed products result, and quick and efficient action of the parts is insured. While the invention has been 80 shown and described in its preferred form, it will be understood that various changes may be made in the specific construction of the spring and its associated parts without departing from the invention as defined in 85 the appended claims. It will be further understood that the invention is not to be restricted to a folding cylinder, but may be used in constructions where a product is transferred by nipping jaws from one position and delivered to the gripping mechanism of a cooperating carrier.

What is claimed is:

1. In a delivery, the combination of a rotary carrier provided with nipping jaws, a 95 cooperating carrier to which the product is delivered provided with sheet taking grippers, means for freeing the product from the nipping jaws and causing it to lie in a line substantially that of the surface of the 100 nipping jaw carrier when released by the jaws, and means for limiting the movement of the freeing means.

2. In a delivery, the combination of a rotary carrier provided with nipping jaws, a 105 cooperating carrier to which the product is delivered provided with grippers, and resilient means on the rotary carrier put under tension by the product and acting to free the product and direct it into the path of 110 the grippers when released by the nipping jaws.

3. In a delivery, the combination of a rotary cylinder provided with nipping jaws, a 115 cooperating cylinder provided with grippers, and spring means on the rotary cylinder compressed by the product as it is taken by the nipping jaws.

4. In a delivery, the combination of a rotary carrier provided with nipping jaws, a 120 cooperating carrier provided with grippers and resilient means against which the product is drawn by the nipping jaws, said means acting to free the product from the jaws and direct it into the path of the grippers.

5. In a delivery, the combination of a rotary carrier provided with nipping jaws, a 125 cooperating carrier provided with grippers, a spring on the rotary carrier against which 130

the product is drawn by the nipping jaws, and stops for limiting the expanding movement of the spring.

6. In a delivery, the combination of a rotary cylinder, a recess in the cylinder wall, nipping jaws located in the recess, a spring located in the recess having a free end and compressed by the product as it is taken by the jaws, a stop in the recess for limiting the expanding movement of the spring, and a cooperating cylinder provided with grippers to which the product is delivered.

7. In a delivery, the combination of a rotary carrier provided with nipping jaws, a cooperating carrier provided with grippers, a spring on the rotary carrier against which the product is drawn by the nipping jaws, and a stop or guide on the spring.

8. In a delivery, the combination of a rotary carrier provided with nipping jaws, a cooperating carrier provided with grippers, a spring on the rotary carrier against which the product is drawn by the nipping jaws, a stop or guide on the spring, and a stop for limiting the expanding movement of the spring.

9. In a delivery, the combination of a rotary carrier provided with nipping jaws, a cooperating carrier provided with grippers, a spring on the rotary carrier against which the product is drawn by the nipping jaws, and means for controlling the expanding

movement of the spring so as to direct a product in a line substantially that of the surface of the rotary carrier.

35

10. In a delivery, the combination of a rotary carrier provided with folding jaws, a cooperating carrier to which the product is delivered provided with grippers, resilient means on the rotary carrier put under tension by the product as it is engaged by the jaws and acting to free the product and direct it into the path of the grippers when released by the jaws, and means for limiting the movement of the resilient means.

40

11. In a delivery, the combination of a rotary carrier provided with nipping jaws, a cooperating carrier provided with grippers, and a flat spring secured at one end on the rotary carrier and free at its other end and put under tension by the product as it is taken by the nipping jaws.

50

12. In a delivery, the combination of a rotary carrier provided with nipping jaws, a cooperating carrier provided with grippers, a flat spring secured at one end on the rotary carrier and free at its other end and put under tension by the product as it is taken by the nipping jaws, and a stop for limiting the expanding movement of the spring.

55

In testimony whereof, I have hereunto set my hand.

HERMAN P. CLAUBERG.
